SPARK PLUG

Application filed August 5, 1927. Serial No. 210,895.

This invention relates to spark plugs, and has for its object the provision of means for effecting a sealing joint between the center electrode and the insulator.

5 The following is a description of a spark plug sealing joint embodying the invention in the form at present preferred; but it will be understood that various modifications and changes may be made without departing 10 from the spirit of the invention and without exceeding the scope of the claims.

The invention will best be understood by reference to the accompanying drawings, wherein Fig. 1 is a view, partly in vertical 15 section and partly in elevation, of a spark plug to which the invention is applied; Fig. 2 is an elevation of the spark plug terminal post and center electrode assembly to which the invention is applied—the ferrule which 20 embodies the invention being shown in section; and Fig. 3 is an elevation of said ferrule.

Like reference characters indicate like parts throughout the drawings.

25 Referring to the drawings, 1 is a shell which may be of conventional type, attached to the lower end of which is ground electrode 2. The bore of the shell is provided with a shou- 30 lder forming a seat for a gasket 3, comprising a sealing joint between said shell and a shoul- 35 dered portion of an insulator 4. The insulator is also provided with an upper shoul- 40 dered portion forming a seat for gasket 5, which, through pressure applied by means 45 of threaded coupling-nut 17, effects a sealing joint in the upper portion of the plug. A center electrode 6 is positioned in the bore of 50 the insulator, such electrode being provided near its upper end with a fluted shoulder por- 55 tion 7. The extreme upper end of the center electrode is adapted to be seated in a recess 13 formed in the lower end of a terminal post, 60 8. The lower portion of the periphery of the terminal post is provided with flutes 9; and 65 the upper end of said post is provided with the usual screw-threads 11 for receiving a terminal nut (not shown). Near its vertical center, the said terminal post is provided with an annular recessed flange 10. The extreme 70 75 lower end of the terminal post is chamfered, 80 85 90 95

as indicated by numeral 14, to provide a seat for a tapered ferrule 15, formed of soft metal.

The invention is applied in the following manner: the ferrule 15 is placed in position upon the fluted shoulder portion 7 of the center electrode 6, as shown in Fig. 2, the upper portion of the ferrule being seated in the chamfered recess 14 of terminal post 8. A quantity of cement, 12, in a plastic state, is then introduced into the bore of the insulator 4, in accordance with the usual custom in this art. The assembly as shown in Fig. 2 is then inserted in the bore of the insulator, and pressure is applied between the terminal post portion of such assembly and the lower end 60 65 70 75 80 85 90 95 of the insulator. This pressure forces the small lower end of tapered ferrule 15 into the lower portion of the insulator bore, simultaneously forces the upper end of the ferrule into the chamfered recess 14 of the terminal post, and upsets or expands the portion of the ferrule intermediate the chamfered recess and the shoulder 18 formed in the insulator. As a result, the lower end of the ferrule is tightly wedged into the small diameter portion of the insulator bore; the upsetting of the upper portion of the ferrule forms a shoulder thereon which is tightly pressed against the shoulder 18 formed in the insulator; and the extreme upper end of the ferrule is seated in intimate contact with the wall of the chamfered recess 14 in the terminal post. It will be understood that the plastic cement 12 enters the flutes 7 and 9 and also fills the annular recess between the shoulder 18 and the upper wall of the recess formed in the terminal post flange 10. It will be obvious that the upsetting or expanding, by pressure, of the upper portion of the ferrule causes pressure upon the surrounding plastic cement, thus insuring an intimate contact thereof with said ferrule.

Following the hereinbefore described processes, heat is applied to the insulator and its associated parts, causing the cement to harden and effecting a firm bond between the various elements. The entire spark plug is then assembled in the usual manner.

The wedging of the ferrule into place, in conjunction with the adhesive action of the

cement, insures a very efficient sealing joint between the center electrode and the insulator. Furthermore, it is, of course, desirable that in the finished spark plug the electrode 6 shall be centrally disposed with reference to the bore of the insulator. The tapered ferrule contributes to this end by reason of the fact that, in assembling the parts in the manner described, it serves as a pilot to centralize the electrode 6. As shown, a slight space is left between the cement 12 and the lower portion of the electrode 6 for the purpose of permitting expansion of this portion of the electrode.

15 I claim:

1. In a spark plug, the combination of an insulator, a center electrode, a soft metal ferrule for effecting a sealing joint therebetween and cement surrounding said ferrule and said electrode.

2. In a spark plug, the combination of an insulator provided with a bore of two diameters and a shoulder therebetween, a center electrode adapted to enter said bore and having a shoulder thereon and a ferrule constructed and arranged to enter the small diameter bore of said insulator and to be upset between the electrode shoulder and the shoulder of the bore in order to effect a sealing joint between said insulator and said electrode.

3. In a spark plug, the combination of an insulator provided with a bore of two diameters and a shoulder therebetween, a center electrode adapted to enter said bore and a terminal post provided with a chamfered recess, and a ferrule constructed and arranged to be upset between said shoulder and said recess in order to effect a sealing joint between said insulator and said electrode.

4. In a spark plug, the combination of an insulator provided with a bore of two diameters and a shoulder therebetween, a center electrode adapted to enter said bore and a terminal post provided with a chamfered recess, and a ferrule constructed and arranged to enter the small diameter bore of said insulator and to be upset between said shoulder and said chamfered recess in order to effect a sealing joint between said insulator and said electrode.

5. In a spark plug, the combination of an insulator, a center electrode, a soft metal ferrule for effecting a sealing joint therebetween, said center electrode being fluted at the region of said ferrule and said electrode and cement surrounding said ferrule and said electrode.

6. In a spark plug, the combination of a center electrode, an insulator having a bore at least a portion of which is of larger diameter than required for fitting purposes with respect to said electrode, said electrode having a shoulder and a ferrule disposed below said shoulder and adapted to be wedged

into the space between the electrode and the insulator bore of such larger diameter, and to abut said shoulder.

7. In a spark plug, the combination of a center electrode, an insulator having a bore of larger diameter than required for fitting purposes with respect to said electrode, and a ferrule of relatively soft, compressible metal adapted to be wedged into the space between the electrode and the insulator bore of such larger diameter.

In testimony whereof I have affixed my signature to this specification.

ROY T. HURLEY.
